US00D876819S

(12) **United States Design Patent** (10) **Patent No.:** **US D876,819 S**
(45) **Date of Patent:** **** Mar. 3, 2020**

(54) **MEDICATION PACKAGING COMBINED
WITH DISPENSING CONTAINER**

(71) Applicant: **AbbVie Inc.**, North Chicago, IL (US)

(72) Inventors: **Lori Kim**, Green Oaks, IL (US);
Alexandra Breban-Lopez, Northbrook,
IL (US); **Guy Upchurch**, Chicago, IL
(US); **Bhimaprasad Medhal**, Lake
Forest, IL (US); **Lewis Sita**, Kildeer, IL
(US); **Dejan Bojicic**, Chicago, IL (US);
John G. Finch, Vernon Hills, IL (US)

(73) Assignee: **ABBVIE INC.**, North Chicago, IL (US)

(**) Term: **15 Years**

(21) Appl. No.: **29/659,875**

(22) Filed: **Aug. 13, 2018**

(57) **CLAIM**

The ornamental design for a medication packaging combined with dispensing container, substantially as shown and described.

DESCRIPTION

FIG. 1 is a front perspective view of a medication packaging combined with dispensing container shown in a closed position;

FIG. 2 is a front elevation view thereof;

FIG. 3 is a rear elevation view thereof;

FIG. 4 is a right elevation view thereof;

FIG. 5 is a left side elevation view thereof;

FIG. 6 is a top view thereof;

FIG. 7 is a bottom view thereof;

FIG. 8 is a front perspective view of the medication packaging combined with dispensing container shown in an open position for ease of disclosure; and,

FIG. 9 is a top plan view of the medication packaging combined with dispensing container shown in the open position.

FIGS. 1-9 are various views of a medication packaging combined with dispensing container in accordance with the present design. The container is adapted to contain a plurality of doses of medication therein.

The broken lines depict portions of the article that form no part of the claimed design.

1 Claim, 9 Drawing Sheets
